(57) CLAIM

The ornamental design of a step accessory, as shown and described.

DESCRIPTION

FIG. 1 is a perspective view showing the step accessory of the present invention;

FIG. 2 is a rear elevational view thereof;

FIG. 3 is a left side elevational view, the right side elevational view being a mirror image thereof;

FIG. 4 is a front elevational view thereof;

FIG. 5 is a top plan view thereof; and,

FIG. 6 is a bottom plan view thereof.

The broken line showing of environment is for illustrative purposes only and forms no part of the claimed design.
